UNITED STATES PATENT OFFICE.

D. W. GEORGE, OF PULASKI, IOWA.

IMPROVEMENT IN WASHING-MACHINES.

Specification forming part of Letters Patent No. 122,596, dated January 9, 1872.

To all whom it may concern:

Be it known that I, D. W. GEORGE, of Pulaski, in the county of Davis and in the State of Iowa, have invented certain new and useful Improvements in Washing-Machine; and do hereby declare that the following is a full, clear, and exact description thereof, reference being had to the accompanying drawing and to the letters of reference marked thereon making a part of this specification.

The nature of my invention consists in the construction and arrangement of a "washing-machine," as will be hereinafter more fully set forth.

In order to enable others skilled in the art to which my invention appertains to make and use the same, I will now proceed to describe its construction and operation, referring to the annexed drawing, in which—

Figure 1 is a side elevation, part in longitudinal vertical section, of my machine, and Fig. 2 is a perspective view of one of the grooved castings in which the rubber is supported.

A represents the tub, made of any suitable dimensions, and provided with a concave bottom in semicircular form. On this bottom is laid and secured a corrugated tin or zinc wash-board, B, which thus forms a semicircle, as shown in Fig. 1. Above each end of the wash-board B is placed an inward-projecting board or ledge, C. The clothes are placed on the board B and washed by being rubbed back and forth by the rubber, which consists of two semicircular heads, E E, connected by means of slats or bars D D inserted in the outer edges of the heads, and a suitable distance apart so as to allow the water to pass between them. The slats or bars D D project beyond the edges of

the heads, and their outer edges are beveled inward toward the center of the rubber, which is of great benefit in drawing the clothes back and forth on the wash-board. In the center of the heads E E, on the outer sides, are points or pivots a a, which are placed in vertical grooves or castings G which are attached to the sides of the tub or box A, said castings thus supporting the rubber and allowing it to give upward according to the amount of clothes to be washed. Across the ends on top of the rubber are secured metal plates H H, which, in combination with the end boards C C, prevent the splashing of the water. Across the top, in the center of the rubber, and also further down, is a cross-bar, I, through which the handle J is passed, as shown. In one side of the tub A is a hole, a', for drawing off the water. In this hole is inserted a bushing, b, with a plug in the same. This bushing prevents the wearing of the hole.

Having thus fully described my invention, what I claim as new, and desire to secure by Letters Patent, is—

The combination of the box A, semicircular corrugated washboard B, end boards C C, rubber D E, plates H H, castings G G, handle J, and bushing b in the hole a', all constructed and arranged substantially as and for the purposes herein set forth.

In testimony that I claim the foregoing I have hereunto set my hand this 10th day of November, 1871.

D. W. GEORGE.
